(21) Appl. No.: **29/167,589**

The ornamental design for a storage bin for a riding lawnmower, as shown and described.

(22) Filed: **Sep. 17, 2002**

DESCRIPTION

(51) LOC (7) Cl. **15-03**

FIG. 1 is a right rear perspective view of a storage bin for a riding lawnmower showing our new design; FIG. 2 is an additional right rear perspective view thereof; FIG. 3 is a right front perspective view thereof; and, FIG. 4 is a left rear perspective view thereof.

(52) U.S. Cl. **D15/17**

The broken line illustration of a riding lawnmower in FIG. 4 is for illustrative purposes only and forms no part of the invention.
